UNITED STATES PATENT OFFICE.

EMANUEL J. LIPSCHUTZ, OF LOUISVILLE, KENTUCKY, ASSIGNOR OF ONE-HALF TO
DAVID LIPSCHUTZ, OF LOUISVILLE, KENTUCKY.

ADJUSTABLE-SIZE CAP.

Application filed August 13, 1927. Serial No. 212,674.

This invention relates to headgear of the type commonly called caps and has for an object the provision of a cap which may be altered in size.

5 Another object of this invention is to provide a cap which may be readily adjusted to fit the wearer, but which is strong and durable and relatively inexpensive to manufacture.

10 Another object of the invention is to so place the adjustment means that no part of it will be exposed to view when the cap is being worn, although it is readily accessible in case it is desired to change the size of the 15 cap.

A further object of the invention is the provision of an adjustable-size cap which may be adjusted to any head size without causing wrinkling or puckering of the outer 20 casing so that its construction may be used in the better grades of caps without detracting from a stylish appearance.

Other objects and advantages will be apparent from a consideration of the detailed description and drawings of headgear embodying the invention.

In the accompanying drawings, which illustrate what I consider to be the preferred forms of the invention:

30 Fig. 1 is a side view of a cap;

Fig. 2 is a front view with the portion of the crown that overhangs the visor lifted;

Fig. 3 is a side-sectional view taken through the center of the cap shown in Fig. 2 with 35 the overhanging portion of the crown in its normal position;

Fig. 4 is a horizontal section taken on line 4-4 of Fig. 3, part of the cap being omitted;

Fig. 5 is a front view of a modification of 40 the invention showing the part of the crown that overhangs the visor raised, and a portion of the front edge of the crown displaced; and

Fig. 6 is a sectional view of the modification shown in Fig. 5, taken on a line 6-6, but with the crown in its normal position.

The improved cap consists mainly of three parts, a crown, a lining, and a visor. The lower edge of the crown constitutes the effective head band, and is formed with an adjustable opening at the front to permit adjustment of the head band. The visor may be attached to the lining but is movably associated with the crown in order to allow

the head band of the crown to be made 55 larger or smaller.

In Figs. 1-4 of the drawing, the numeral 1 indicates the crown of the cap, the lower edge portion thereof constituting the head band 2. The head band is reinforced internally with a stiffening tape 3 of suitable strong material. At the front of the cap, the head band portion of the crown is split as at 4, and is provided with any suitable adjustment means such as straps 5 and 6, of suitable material such as flexible leather, and a buckle 7. The buckle 7 may be engaged in any of the perforations 8 of the strap 5 to regulate the width of the opening 4 and consequently adjust the size of the head 70 band 2 of the cap. It is, of course, obvious that any other suitable form of adjustment means could be substituted for that shown.

A lining 20 is positioned within the crown 1. This lining may cover the entire inside 75 of the crown, as illustrated, or may extend only within the head band portion. The lower edge 21 of the lining 20 may be secured to the head band, by stitching or other suitable means, at the back and along 80 the sides as far front as the points designated A, in Figs. 3 and 4 of the drawing, which points are spaced from the ends of the visor. Forwardly of the points A the lining is left free of the crown.

The visor 40 is preferably of the type usually employed in ordinary caps, and consists of a piece of relatively stiff material 41 of substantial thickness, covered by fabric 42 similar to that of the crown 1. The edges 90 of the covering fabric 42, along the inner edge of the visor, are preferably extended as at 43, and to these edges is secured the front part 22 of the lower edge 21 of the lining 20.

The points designated B indicate the extremities of the attachment of the lining to the visor. It is to be noted that these points B are spaced from the points A, and that, between these points, the lower edge of the lining is capable of wrinkling, or folding, or straightening out according to whether the cap is adjusted to a small or large head size. This wrinkling or folding of the lining is entirely within the cap and not exposed to view when the cap is being worn. The portions of the lining between the points A and B are designated by nu-

meral 23. These portions of the lining constitute flexible connections between the ends of the visor and the head band.

A sweat band 44 may be attached to the inner edge of the visor, if desired.

Secured to the extensions 43 of the visor covering and positioned between the lining and the material of the crown is a flap 45, shown in dotted lines in Fig. 2, preferably 10 of the same material as the crown 1. This flap is positioned at the front of the cap, and underlies the opening 4 of the crown.

Secured to the extensions 43 of the covering of the visor, as by spaced rivets 46, is a 15 flexible guide strip 47 of any suitable material, such as celluloid. This guide strip is not essential in the construction of this improvement, the broad concept being entirely independent of this feature. In the 20 form of the invention illustrated in Figs. 2, 3 and 4, the guide strip may be employed to good advantage to provide a guideway for the front part of the lower portion of the crown. Along the inside of this portion of 25 the crown are formed spaced loops 48 which encircle the guide strip 47 between the spaced rivets 46. The head band is not otherwise attached to the inner edge of the visor, thereby permitting the head band to be 30 moved relative to the visor in adjusting the size of the cap.

The portion of the crown 1 that overhangs the visor and the visor are preferably provided with some means, such as the usual 35 knob 49 and resilient socket 50, for detachably securing the two together.

The embodiment of the invention, illustrated in Figs. 5 and 6, is different from the above described embodiment principally in 40 that it eliminates the use of a guide strip for the front portion of the head band. In this embodiment a lining 20' is secured within a crown 1' in the same manner as in the first embodiment, the extremities of 45 this attachment being indicated by A', in Fig. 6. A visor 40', similar to that before described, is attached to the lower edge of the front of the lining, the ends of the visor being spaced from the points A'. Flexible 50 connections are thereby provided between the ends of the visor and the head band. An opening 4' is provided in the front of the crown 1', and means, such as straps 5' and 6' and buckle 7', is provided for adjusting 55 the size of the cap.

Underlying the material of the crown at the front of the cap, and secured to the inner edge of the visor is a flap 45', shown in dotted lines in Fig. 5, which extends the 60 entire width of the visor.

The front of the head band, being unattached to the visor, can move relatively thereto in adjusting the size of the cap.

A loop 9 may be attached to the inner 65 edge of the visor for the purpose of encir-

cling the strap 5' to keep it close to the visor. Some means such as the knob 49' and resilient socket 50' may be provided for detachably securing the overhanging portion of the crown to the visor.

70

It is readily apparent in both of the above described embodiments that when the opening at the front of the crown is drawn together, the effective head size of the cap becomes smaller. When the width of said 75 opening is increased the head size of the cap becomes larger.

It is apparent that no matter how the cap may be adjusted, no wrinkling of the outer casing of the crown will occur. Furthermore, the adjustment means being located at the front of the cap, and covered by the overhanging part of the crown, when the cap is being worn, there will be nothing to indicate to an observer that the cap is adjustable. The cap will therefore present the same stylish appearance as a non-adjustable cap of like quality.

80

I claim:

1. A cap comprising a crown with the lower portion thereof constituting a band which determines the head size of the cap, means located at the front of the crown for adjusting the effective head size of the band, and a visor, the inner edge of which is associated with the front of the band, the front of the band being movable relative to the inner edge of the visor throughout the entire extent of said edge to permit adjustment of the effective head size of the band.

85

2. A cap comprising a crown with the lower portion thereof constituting a head band, an adjustable opening at the front of the crown for regulating the size of the band, a visor associated with the front portion 105 of the crown and connected to the band at its inner edge in a manner to permit movement relative thereto in adjusting the band to effect a change in the size thereof.

100

3. In an adjustable-size cap, a crown, the lower portion of which forms a head band, a lining, a visor, the lining being attached to the inner edge of the visor adjacent its ends, and attached to the head band at points spaced from the ends of the visor, an 110 opening in the crown at the front adjacent the inner edge of the visor, and means for adjusting the width of the opening to regulate the effective head size of the band.

115

4. An adjustable-size cap comprising a 120 crown having an opening at the front, means for adjusting the width of the opening, a lining within the crown and secured thereto at the back and sides, a visor attached to the front of the lining, and a flap secured 125 to the inner edge of the visor and underlying the opening in the crown.

120

5. In an adjustable size cap, a crown, a visor located at the front of the crown, a 130 head band composed of the lower portion of

135

the crown and adjustable means supplementing the length thereof, the adjustable means constituting the extreme front part of the band, the entire front part of the band being slidably circumferentially relative to the visor.

6. An adjustable size cap comprising a lining, a visor attached to the lower front edge of the lining, a crown secured to the lower edge of the lining along the back and sides up to points spaced from the ends of the visor, the front of the crown being movably associated with the lining and visor, an opening formed in the front crown from its lower edge upward and means by which the width of the opening may be adjusted.

7. An adjustable size cap comprising a body portion forming a crown, an opening in the crown from its front lower edge upward, a visor associated with the front of the crown, flexible means for connecting the ends of the visor to the lower edge of the crown at the sides of the cap to permit relative movement therebetween, and means for adjusting the width of the opening to regulate the head size of the cap.

8. An adjustable size cap comprising a crown, a visor associated with the front of the crown, the crown having a portion overhanging the visor and being provided with means for changing the size of the cap comprising an adjustable width opening therein, said opening being concealed between the overhanging portion of the crown and the visor.

9. In an adjustable size cap a crown having an opening from its front lower edge upward, the lower edge portion of the crown constituting a head band, an apertured strap attached to one edge of the opening, a strap attached to the other edge of the opening, a buckle secured to the second strap and

adapted to engage in any of the apertures of the first strap, a visor at the front of the cap, a lining within the crown, means for attaching the rear and side lower edges of the lining to the head band, means for attaching the inner edge of the visor to the front lower edge of the lining, there being portions of the lower edge of the lining at the sides thereof unattached to either the head band or the visor and forming means whereby the visor is permitted to move relative to the head band when the effective head size of the band is being adjusted.

10. An adjustable size cap comprising a lining, a crown secured to the lining along the back and sides thereof, a visor attached to the lining along its inner edge, the ends of the visor being attached to the lining at points forwardly spaced from the termination of the attachment of the lining and crown, a guide strip secured to the visor adjacent the inner edge thereof, an opening in the crown at its front, means for adjusting the width of the opening, and means formed on the crown for slidably engaging the guide strip.

11. An adjustable size cap comprising a crown, the lower portion thereof constituting a band the effective length of which determines the head size of the cap, a visor associated with the lower front edge of the crown, flexible means for attaching the ends of the visor to the band to allow relative movement therebetween, a guide strip attached to inner edge of the visor at spaced points, means upon the front part of the band for slidably engaging the guide strip, and means at the front of the band for adjusting its effective length to regulate the head size of the cap.

EMANUEL J. LIPSCHUTZ.
